UNITED STATES PATENT OFFICE.

HARRY COHN, OF BROOKLYN, NEW YORK, ASSIGNOR TO ROBERT FINDLAY MANUFACTURING CO., OF NEW YORK, N. Y., A CORPORATION OF NEW YORK.

DESIGN FOR LIGHT-REFLECTING BOWL.

54,232.

Specification for Design.

Patented Dec. 2, 1919.

Application filed March 2, 1918. Serial No. 220,057. Term of patent 7 years.

To all whom it may concern:

Be it known that I, HARRY COHN, a citizen of the United States, residing at Brooklyn, in the county of Kings and State of New York, have invented a new, original, and ornamental Design for a Light-Reflecting Bowl, of which the following is a specification, reference being had to the accompanying drawing, forming part thereof.

The figure is a perspective view of a light reflecting bowl of the configuration, and bearing the ornamentation as shown on the drawing.

I claim:

The ornamental design for a light reflecting bowl, as shown.

HARRY COHN.
